VACUUM CLEANER

Filed April 23, 1927

By *Watson E. Coleman*
Attorney

UNITED STATES PATENT OFFICE.

JOHN E. ARDELL, OF TYRONE, PENNSYLVANIA.

VACUUM CLEANER.

Application filed April 23, 1927. Serial No. 186,084.

This invention relates to vacuum cleaners.

An important object of the invention is the provision of a device of this character with a beater embodying spring fingers, which tap 5 against the surface over which the cleaner is passing to jar therefrom any embedded dirt or dust.

A further object of the invention is to provide a construction of this character, which 10 permits a device of this type to be employed in combination with a rotatable brush arranged in the mouth of the nozzle, such as is now employed with certain types of vacuum cleaners.

15 A further object of the invention is to produce a device of this character which may be readily and cheaply incorporated in the vacuum cleaner construction, which will be durable and efficient in service and a general 20 improvement in the art.

These and other objects I attain by the construction shown in the accompanying drawings, wherein for the purpose of illustration is shown a preferred embodiment of my invention and wherein:

Figure 1 is a plan view partially broken away of a vacuum cleaner constructed in accordance with my invention;

Figure 2 is a side elevation thereof, portions being broken away to show the interior construction.

Referring now more particularly to the drawings, the numeral 10 indicates a motor casing of the vacuum cleaner, 11 the casing 35 of a suction fan driven from one end of the armature shaft 12 and 13 the casing of a pulley 14 secured to the opposite end of the armature shaft. Extending from the intake of the fan casing 11 is a suction nozzle 12, the 40 terminal portion of which confronts the surface over which the motor 10 is passing in the usual manner. Arranged within the mouth of this suction nozzle and rotatably supported by the end walls 15 thereof is a brush 16, which may be of any usual or preferred construction.

In accordance with my invention, one end wall 17 of the suction nozzle is continued 50 downwardly and rearwardly from the suction nozzle to form the end wall of a compartment 18, the upper wall of which is formed by the bottom wall 19 of the suction nozzle or a continuation 20 thereof. The compartment 18 has a second end wall 21 and a rear wall

22, the lower ends of which terminate in the 55 same plane as the mouth 15 of the nozzle. Mounted in the end walls 17 and 21 immediately to the rear of the bottom walls 19 of the nozzle at the mouth thereof is a roller R having longitudinally spaced cam elements 60 23. Secured to the rear wall and extending forwardly in the plane of the lower edge of the walls of the compartment 18 are spring tongues 24, each having at its forward end an upturned end portion provided at its extremity with a tip 25 extended into the path of one of the cams 23. The roller R is driven by a belt 26 from the pulley 14 and this roller is in turn connected with the brush 16 by a belt 27. The spring fingers 24 are made as 70 narrow as possible and the cams 23 may be either uniformly spaced about the roller R, or may be arranged in groups, which are uniformly spaced, so that no sudden load will be thrown against the mechanism of the vacuum cleaner to prevent a smooth operation 75 thereof.

It will be obvious that as the roller rotates, the forward ends of the springs 24 will be elevated by engagement of the cams 23 80 with the rearwardly directed terminal portions 25 and after being placed under tension, will be suddenly released, so that they will move downwardly and engage the surface over which the cleaner is passing. A 85 tapping action is thus provided, which will serve to jar loose from the surface particles of dirt, which otherwise would adhere thereto with sufficient force to prevent their removal either by the brush or suction nozzle. 90

It will of course be understood that the entire structure will be mounted upon suitable casters 28 and provided with the usual handle 29.

Since the construction hereinbefore set 95 forth is capable of a certain range of change and modification without materially departing from the spirit of the invention, I do not limit myself to such specific structure except as hereinafter claimed.

I claim:

In a vacuum cleaner, a supporting frame, a motor thereon, a pump casing having a pump therein operated by the motor, a nozzle connected to the casing and in communication 105 with the pump, said nozzle being extended laterally from the casing and terminating in a downwardly directed elongated suction

mouth, a support beneath the nozzle and spaced from the nozzle mouth, a plurality of fingers secured at one end to the support with their free ends terminating in hooks adjacent to and in a line parallel to the nozzle mouth, means operated by the operation of the motor for intermittently elevating the free ends

of said fingers and suddenly releasing the same, and an open-bottomed housing for said fingers comprising in part the bottom wall 10 of said nozzle.

In testimony whereof I hereunto affix my signature.

JOHN E. ARDELL.
